WRIST SUPPORT

Norman S. Borenstein, Tustin, Calif., assignor to
Masters Industries, Inc., Irvine, Calif.

Filed Feb. 11, 1974, Ser. No. 441,018

Term of patent 14 years

Int. Cl. D24—04

U.S. CL. D83—1 J

FIG. 2.

FIG. 1.

FIG. 3.

FIG. 6.

FIG. 4

FIG. 5.

FIG. 1 is a top plan view of a wrist support embodying my new design;

FIG. 2 is a bottom plan view of the wrist support of FIG. 1;

FIG. 3 is a side elevational view of the wrist support;

FIG. 4 is a top plan view of a wrist support embodying a modified version of my design;

FIG. 5 is a bottom plan view of the wrist support of FIG. 4; and

FIG. 6 is a side elevational view of the wrist support of FIGS. 4 and 5.

I claim:

The ornamental design for a wrist support, as shown and described.
